US00D985015S

(12) **United States Design Patent** (10) **Patent No.:** **US D985,015 S**
Kanamaru et al. (45) **Date of Patent:** **** May 2, 2023**

(54) **DISPLAY SCREEN OR PORTION THEREOF WITH GRAPHICAL USER INTERFACE**

(71) Applicant: **FURUNO ELECTRIC CO., LTD.**, Hyogo (JP)

(72) Inventors: **Naohiro Kanamaru**, Nishinomiya (JP); **Kohji Nishiyama**, Nishinomiya (JP); **Kentaroh Hamamoto**, Osaka (JP)

(73) Assignee: **FURUNO ELECTRIC CO., LTD.**, Hyogo (JP)

(**) Term: **15 Years**

(21) Appl. No.: **29/805,092**

(22) Filed: **Aug. 25, 2021**

(30) **Foreign Application Priority Data**

Feb. 26, 2021 (JP) ..... 2021-003988 D

CLAIM

The ornamental design for a display screen or portion thereof with graphical user interface, as shown and described.

DESCRIPTION

The FIGURE is a front view of a display screen or portion thereof with graphical user interface showing our new design.

The outermost dot-dash broken lines illustrate a display screen or portion thereof and form no part of the claimed design. The remaining broken lines, illustrating portions of the graphical user interface, form no part of the claimed design.

1 Claim, 1 Drawing Sheet
